(57) **CLAIM**

The ornamental design for a window mounting bracket for an antenna, as shown and described.

DESCRIPTION

FIG. 1 is a perspective view of a window mounting bracket for an antenna showing my new design.

FIG. 2 is a front elevational view thereof.

FIG. 3 is a left side elevational view thereof, with the right side elevational view being a mirror image of FIG. 3.

FIG. 4 is a rear elevational view thereof.

FIG. 5 is a top plan view thereof; and,

FIG. 6 is a bottom plan view thereof.
